R. H. MacINNES
INSULATION BLOCK AND ELECTRICAL CONNECTION FOR THE BURNERS
OF ELECTRIC RANGES
Filed May 24, 1923

INVENTOR
ROBERT H. MACINNES
BY *R. H. MacInnes*
A.M.A.

UNITED STATES PATENT OFFICE.

ROBERT H. MACINNES, OF HAMILTON, ONTARIO, CANADA, ASSIGNOR TO D. MOORE COMPANY, LIMITED, OF HAMILTON, ONTARIO, CANADA.

INSULATION BLOCK AND ELECTRICAL CONNECTION FOR THE BURNERS OF ELECTRIC RANGES.

Application filed May 24, 1923. Serial No. 641,264.

To all whom it may concern:

Be it known that ROBERT H. MACINNES, a subject of the King of Great Britain, residing at Hamilton, in the county of 5 Wentworth and Province of Ontario, Canada, has invented certain new and useful Improvements in Insulation Blocks and Electrical Connections for the Burners of Electric Ranges, of which the following is a 10 specification.

My invention relates to improvements in electric ranges and more particularly the electrical connections of the resistance wiring or heating element to the lead wires 15 connected with the source of electricity, and consists essentially of an insulation block interposed between two electric burners, provided with a pair of ribs between which the lead wires are carried, each parallel with 20 the adjacent sides of a burner and having a plurality of transverse grooves for containing the terminals, and partitions interrupting said grooves and through which conductance rods are passed leading from one 25 terminal to the other.

The principal object of the invention is to generally improve the construction of the electrical connections of electric ranges, at the same time producing an efficient, simple, 30 and inexpensive device.

These, together with other objects may be attained by the construction, combination and arrangement of the parts as will be hereinafter more fully described, illustrated 35 in the accompanying drawing and pointed out in the specification hereunto annexed.

Referring to the drawing:

Figure 1 is a bottom view of the cover or top plate of a range showing the improved 40 electrical connections, together with one burner, the other burner being removed; and,

Figure 2 is a cross-sectional elevation of Figure 1 taken on the line 2—2.

Similar reference characters refer to similar parts throughout both views.

The cover or top plate A of the range is formed to accommodate two electric burners B which are disposed so that their top surfaces are substantially flush with the top surface of the cover plate and supported by a plurality of depending seats 2 integral with said cover plate and suitably arranged along the edges of the holes in which the burners

are inclosed. Interposed between the two 55 burners B is the insulation block C which may be secured to the bottom of the cover plate A by the bolts 3, for example, and formed preferably of porcelain or other suitable insulation material. The outer 60 edges of this block are shaped to conform to the contour or outline of the cover plate holes in which are confined the burners B, and are preferably arranged in vertical alignment with the edges of said holes. A 65 pair of ribs 4 are formed on the block C, each being parallel with the burner 3 to which it is adjacent and intersecting these ribs are a plurality of transverse grooves 5. These grooves are however interrupted by 70 partitions 6 which project to an extent lower than the terminations of the ribs 4. Through these partitions are passed conductors in the form of bolts 7 to the inner ends of which are connected the lead wires 8. To 75 the opposite ends of the conductors 7 are connected spring terminal lugs 9 which occupy the grooves 5 and tensionally engage the spring terminal lugs 10 which are secured to the burners B and connected to the 80 resistance wiring or heating element 11 thereon. The spring terminal lugs 10 occupy grooves 12 in the burner, as shown.

There has thus been provided a simple and efficient device of the class described 85 and for the purpose specified.

Having now fully described my invention, what I claim and desire to secure by Letters Patent, is:—

1. In combination with the cover plate 90 and electric burners of a range, an insulation block interposed between the burners, ribs formed on the block paralleling the burners and intersected by grooves, partitions spanning said grooves, electrical conductors extending through said partitions, and terminals on the ends of said conductors nearest the burners and engaging terminals on the burners, the opposite end of said conductors being connected to lead 100 wires.

2. In combination with the cover plate and electric burners of a range, an insulation block interposed between the burners, a plurality of ribs arranged on the block in 105 parallel relation with the burners, electrical conductors extending through said ribs, and terminals on the ends of said conductors

nearest the burners and engaging terminals on the burners, the opposite end of said conductors being connected to lead wires.

3. In combination with the cover plate and electric burners of a range, an insulation block interposed between the burners and intersected by grooves, partitions spanning said grooves, electrical conductors extending through said partitions, spring terminals on the ends of said conductors nearest the burners, the opposite ends of said

conductors being connected to lead wires, and spring terminals secured to said burners and tensionally engaging the former terminals.

In testimony whereof I have affixed my signature.

ROBERT H. MACINNES.
